United States Patent Office

Des. 205,143
Patented June 28, 1966

205,143

AERIAL SPINNING TOY

Robert Plante, 4 Grace St., North Aurora, Ill.

Filed Aug. 5, 1965, Ser. No. 86,460

Term of patent 14 years

(Cl. D34—15)

FIG. 1.

FIG. 2.

FIG. 3.

FIG. 4.

FIG. 1 is an elevational view of one of the two like sides of an aerial spinning toy, showing my new design; FIG. 2 is a bottom edge view thereof; FIG. 3 is a view of one end thereof; and FIG. 4 is a view of the other end thereof.

I claim:

The ornamental design for an aerial spinning toy, substantially as shown and described.
